Primary Examiner — George D. Kirschbaum

Assistant Examiner — Lillian Windham

(57) **CLAIM**

The ornamental design for a room sensor display, as shown and described.

DESCRIPTION

1.1: Front

1.2: Back

1.3: Left

1.4: Right

1.5: Bottom

1.6: Top; and

1.7: Perspective

The broken lines in the figures are for the purpose of illustrating portions of the room sensor display that are not part of the claimed design.

1 Claim, 7 Drawing Sheets(56)
